COMBINED AIR PRESSURE RELEASE AND COVER FOR BOTTLES AND THE LIKE

Filed Nov. 13, 1922

Inventor
THOMAS W. SLACK.

By A. D. Jackson

Attorney

UNITED STATES PATENT OFFICE.

THOMAS W. SLACK, OF FORT WORTH, TEXAS.

COMBINED AIR-PRESSURE RELEASE AND COVER FOR BOTTLES AND THE LIKE.

Application filed November 13, 1922. Serial No. 600,539.

To all whom it may concern:

Be it known that I, THOMAS W. SLACK, a citizen of the United States, residing at Fort Worth, in the county of Tarrant and State of Texas, have invented certain new and useful Improvement in Combined Air-Pres-
5 sure Releases and Covers for Bottles and the like, of which the following is a speci-
fication.

10 My invention relates to air-pressure re-
lease devices and covers for water bottles
and the like; and the object is to provide
simple devices for aiding in pouring water
from bottles and for closing the mouths of
15 the bottles. It is well known that in bottles
or vessels having small outlet ports for
liquids, the liquids will gurgle while being
poured out and frequently the liquid will
be splashed or thrown on the floor or other
20 place and that the cause of this is the air
pressure. The object of this invention is to
provide a simple device which can be pro-
vided at small cost and which will automati-
cally release the air pressure and to attach
25 to the device a cover for the bottle or the
like. Other objects and advantages will be
fully explained in the following description
and the invention will be more particularly
pointed out in the claims.

30 Reference is had to the accompanying
drawings which form a part of this applica-
tion.

Fig. 1 is a side elevation of the devices,
35 shown applied to a bottle neck and a por-
tion of the body, partly in section. Fig.
2 is a front elevation of the devices. Fig.
3 is a plan view of a bottle, showing the de-
vices applied to the bottle and the lid thrown
40 back out of closing position.

Similar characters of reference are used to
indicate the same parts throughout the sev-
eral views.

The air-release includes a bent tube 1
which is to be projected down into the bottle
45 and at the opposite side from the direction
of the tilting of the bottle. The tube 1 is
held in place in the bottle neck and mouth
by a spring which has two arms 2 which
bear against the interior of the bottle neck
50 and which bear on the opposite side of the

neck from the tube 1. A loop 3 is formed of
the upper part of the wire and this loop 3
rests on top of the bottle and will prevent
the spring from going down into the bottle.
The spring is soldered or otherwise at-
55 tached to the sides of the tube 1. The tube
1 is thus safely mounted in the neck and
mouth of the bottle and will not be dis-
lodged in pouring liquid from the bottle.
The cover or lid 4 is a flat piece of metal 60
which is hingedly connected to the loop 3
of the wire. The wire 2 may be soldered
or otherwise attached to the tube 1. The
spring will hold the tube 1 in place. The
device can readily be mounted and removed 65
from the bottle. The main function of the
tube 1 is to admit air into the bottle for re-
lieving the air pressure. When this is done
the water or other liquid in the bottle will
run out in a steady stream and will run 70
freely, not being retarded by air-pressure.
The lid or cover 4 will rest loosely on the
mouth of the bottle for closing the bottle.
The lid 4 can be swung back and hang down
while water is being poured or the lid may 75
be pressed open by the flowing water to ap-
proximately the dotted outline position of
Fig. 1 relative to the mouth of the bottle
while the water is being poured. Various
80 changes in the sizes, proportions, construc-
tion and arrangement of the parts may be
made without departing from my inven-
tion.

The spring 2 will hold the tube 1 approx-
imately in the positions shown in Figs. 1 85
and 3 of the drawings so that air will pass
down the tube into the bottle when the
bottle is tilted to pour out water or other
liquid. The lower end of the tube will never
be under the surface of the liquid when the
90 bottle or other receptacle is tilted in the op-
posite direction from the tip of the pipe.
The liquid will flow out in a steady stream
and will not gurgle and splash the liquid
where it is not wanted.

What I claim, is,—

1. An air-pressure releaser for bottles and
the like comprising a bent tube open at both
ends and projected down into the bottle
and a bent spring having a loop resting on 100

top of the bottle and having a portion of the arms attached to the side of the tube and the free ends bearing against the opposite side of the bottle neck.

5 2. An air-pressure releaser and lid for bottles and the like comprising an open bent tube projected down through the neck of a bottle into the bottle, a spring having a loop

resting on top of the bottle and having portions of the arms attached to the tube and the free ends pressing against the opposite side of the bottle, and a lid for the bottle hingedly connected to said loop.

In testimony whereof, I set my hand, this 30th day of October, 1922.

THOMAS W. SLACK.
